WAVE GUIDE FEED

William Sichak, Cambridge, Mass., assignor, by
mesne assignments, to the United States of
America as represented by the Secretary of the
Navy

Application September 17, 1945, Serial No. 616,920

5 Claims. (Cl. 250—33.63)

1

My present invention relates in general to wave guide means for interchanging electric waves between radio apparatus and free space, and in particular to an open ended wave guide having radiation that is substantially uniformly distributed over the region before the opening.

It is well known that an open ended wave guide will function as an antenna having a broadly directional beam pattern at the open end. For example, a rectangular wave guide may have a beam pattern that is approximately 120° wide, extending 60° each side of the projection of the guide axis. When it is desired to feed certain types of reflectors with an open ended wave guide radiator, as for example, a pill box type or other cylindrical parabolic reflector, with the open ended wave guide located at the principle focus thereof, a beam of 180° width is desirable. A simple open ended wave guide will not produce such a beam and is therefore not suitable as a feed for such reflectors.

It is accordingly an object of my invention to provide an open ended wave guide type antenna which will produce a beam having a width of substantially 180°.

It is another object of my invention to provide such an antenna that will be simple to construct and will not cause undesired reflections or modes of oscillation.

It is a further object of my invention to provide means for broadening the beam of an open ended wave guide antenna which means may be used on wave guides of all sizes without interfering with the normal operation of such wave guides.

My present invention accomplishes the above and other objects by providing at the open end of a wave guide one or more pairs of oppositely located projections on the walls of the wave guide about the open end, these projections extending substantially longitudinally with respect to the wave guide and forming extensions of selected portions of the walls thereof. The manner in which my invention accomplishes these and other objects and features of my invention will become apparent upon a careful consideration of the following detailed description when taken together with the accompanying drawing, the figures of which illustrate typical embodiments of the invention.

Fig. 1 is a perspective view of an embodiment of my invention;

Fig. 2 is a top view of the apparatus of Fig. 1;

Fig. 3 is a top view of a second embodiment of my invention;

2

Fig. 4 is a cross section along the line IV—IV of Fig. 3;

Fig. 5 is a top view of still another embodiment of my invention; and

Fig. 6 is a cross section along the line VI—VI of Fig. 5.

Although my invention may be used with any type of wave guide, I prefer herein to illustrate the principles thereof as embodied in rectangular wave guides. Accordingly in Fig. 1, a rectangular wave guide 1 having an open end 2, narrow walls 3, and wide walls 5 has two projections 4 positioned one on each narrow wall 3. The projections 4 are each narrower than the wall 3 on which respectively located, the width h of each of said projections being substantially one-half or slightly less than one-half the width of a wall 3. Each projection 4 preferably extends outwardly longitudinally with respect to the wave guide 1 a distance approximately equal to one-half the free space wave length of the energy carried by said wave guide 1. The projection 4 may be soldered to the wall 3 or may be formed integral with the wave guide 1 by milling or sawing away portions of the wide walls 5 near the open end 2 thereof.

The embodiment of my invention illustrated in Figs. 3 and 4 is similar to the apparatus of Figs. 1 and 2, having on the narrow walls 3 of the rectangular wave guide 1 an oppositely located pair of projections 6 similar to the projections 4 in Fig. 1. In addition, however, a second pair of projections 7 are similarly oppositely positioned on the wide walls 5 of the rectangular wave guide 1. The first pair of projections 6 preferably extend outwardly from the opening 2 a slightly greater distance than the second pair of projections 7. The respective widths of the projections 6 and 7 may be determined experimentally to provide the desired beam pattern. In all cases a projection is substantially narrower than the wall on which it is mounted, similarly to the projections 4 in Fig. 1. Each projection may be soldered to the wall of which it forms a partial extension or may be simply an extension of the material of that wall.

Another embodiment of my invention illustrated in Figs. 5 and 6 is similar to the embodiment of Figs. 3 and 4 except that the corners of the rectangular wave guide 1 are cut diagonally rather than rectangularly as in the previous embodiment. This provides pairs of projections 8 and 9, having slanted rather than rectangular edges 10.

Returning now to Figs. 1 and 2 and particularly to Fig. 2, the apparatus of my invention therein

illustrated operates to produce a beam having a width of substantially 160° in a plane parallel to a wide wall 5 of the wave guide 1, extending substantially 80° on each side of an imaginary projection of the longitudinal axis of said wave guide. The width of this beam is measured at the ten decibel drop point from the peak intensity of the beam. Radiation appears to be centered at a point P which is in the neighborhood of one-sixteenth of a wave length in front of the opening 2. This beam extends thus substantially uniformly about the region in front of the opening 2 and is suitable for feeding cylindrical parabolic reflectors of various types, as for example, of the pill box type. The embodiments of my invention illustrated in Figs. 3 and 6 inclusive operate to produce a beam similar to that produced by the apparatus of Figs. 1 and 2. The additional pair of projections on the wide walls 5 of the wave guide 1 have influence upon the width of the beam pattern in the plane parallel to the narrow walls 3.

The embodiments of my invention herein illustrated are to be regarded as illustrative only and not the only manner in which my invention may be practiced. I prefer that my invention be limited only as necessitated by the prior art and the spirit of the appended claims.

I claim:

1. Apparatus for the interchange of electric waves between radio equipment and free space comprising, an open ended rectangular wave guide and first and second pairs of oppositely located substantially longitudinally outwardly extending projections mounted on the narrow and wide walls respectively of said wave guide about the open end thereof, each of said projections substantially forming an extension of one of said walls having substantially the same thickness but lesser width than said wall, the projections of said first pair extending outwardly a greater distance than the projections of said second pair.

2. Apparatus for the interchange of electric waves between radio equipment and free space comprising, an open ended rectangular wave guide and a pair of substantially longitudinally outwardly extending conductive projections mounted oppositely on the narrow walls of said wave guide about the open end thereof substantially to form extensions of said walls, said pro-

jections being of substantially the same thickness but of lesser width than said walls.

3. Wave guide radiating apparatus comprising, an open ended rectangular wave guide presenting two narrow and two broad walls having an inner conductive surface and first and second pairs of projections oppositely disposed on the narrow and broad walls, respectively, of said wave guide about the open end thereof, each of said projections defining a conductive partial continuation of said inner conductive surface, each of said conductive surface continuations extending outwardly of said open end substantially in the direction of the longitudinal axis of said wave guide, said projections at said narrow walls extending outwardly a greater distance than the projections at said broad walls.

4. Apparatus as defined in claim 3 wherein said conductive surface continuations are rectangular.

5. Wave guide apparatus comprising, a rectangular wave guide having an end apertured in a plane transverse to its longitudinal axis, first and second pairs of projections mounted oppositely at said apertured end on the narrow and broad walls respectively of said wave guide, each of said projections extending outwardly from said apertured end substantially in the direction of the longitudinal axis of said wave guide, each of said projections having uniform trapezoidal transverse cross sections throughout its longitudinal length, each of said projections having a width that is substantially less than the width of the wall from which it projects.
